MULTIPLE GAP ARC INTERRUPTER

Ralph R. Pittman, North Little Rock, Ark.

Application July 12, 1946, Serial No. 682,989

8 Claims. (Cl. 175—30)

1

This invention relates to excess voltage protective devices for use in limiting the voltage which may be superimposed on an electrical circuit and extinguishing a power arc which may follow an impulse discharge caused by the superimposed voltage.

Among the objects of the invention may be noted, (a) the provision of a sparkover or discharge path which includes in series circuit arrangement a plurality of spark gaps so cooperating with other elements of the construction that under voltage stress the sum of the voltages appearing across the individual gaps greatly exceeds the voltage impressed across the device; (b) the provision of a construction in which the division of voltage between the serially arranged gaps remains substantially constant regardless of rate of change in applied voltage; (c) the provision of a construction in which sparkover of a sufficient number of gaps to effect arc extinguishment is accomplished at a protective voltage level much less than is possible with a simple series arrangement of gaps, without more, connected to bridge the circuit; (e) the provision of a multiple gap arc interrupter having spark gaps in series in which a definite voltage may be made to appear concurrently across each of the multiple gaps when a predetermined voltage is impressed across the terminals of the device, the definite voltage across each gap being only slightly less than the terminal voltage; (f) the provision of a device embodying a series of spark-gaps in which sparkover of all gaps occurs concurrently as opposed to the cascade type of flashover common in multiple series gap devices; (g) a device embodying a plate condenser with serially arranged plates in which the respective plates of the condenser are formed to provide a series of spark gaps from one end plate of the condenser to the other, the gaps so cooperating with the condenser plates that the latter are serially connected in response to sparkover in a manner differing from the seriatim order of plates from one end of the condenser to the other; and (h) the provision of a construction requiring only simple and inexpensive parts and assembly. Other objects and advantages will appear from the following description.

The invention is exemplified by the form, combination and relationship of the parts shown in the accompanying drawing and described in the specification, and the scope of the invention is particularly pointed out in the appended claims.

In its broadest aspect, the circuit arrangement of the invention is similar in some respects to the

2

construction shown in my copending application Serial No. 666,902, filed May 3, 1946, which has matured into Patent No. 2,427,975, September 23, 1947.

Fig. 1 of the drawing is an elevation, shown partly in section of an embodiment of the invention; Figs. 2 and 3 are respectively sectional views taken along the lines 2—2 and 3—3 of Fig. 1; Fig. 4 is a fragmentary sectional view showing the relationship of the conducting members to the insulating members; and Figs. 5, 6 and 7 show diagrammatically the circuit arrangement or equivalent circuit arrangement of the structure.

As the drawing shows, the embodiment presented here is particularly adapted for limiting excess voltage, such as might be caused by lightning, of low or so-called utilization voltage circuits, e. g. 120—240—480—650 volts, but it will appear that the range of application may be extended to higher circuit voltages by simply adding additional elements in quantities greater than illustrated.

Currently low voltage lightning arresters or by-pass devices designed for application to power circuits, include one spark gap, functioning to prevent leakage current under normal conditions, and an arc extinguishing element having resistance for limiting the power follow current to a sufficiently small value to prevent sustained arcing following sparkover. The impedance drop attending the passage of the surge current through the resistance is impressed upon the connected apparatus, in some cases resulting in connected apparatus flashing over or puncturing of insulation if the resistance is too great, or the thermal destruction of the resistance element if the resistance is too low.

The present invention provides a construction embodying no resistance element, substituting therefor a novel arrangement of elements including a series arrangement of arcing gaps to cause arc extinguishment without practical sacrifice of protective level. It is well known that a series of short arcs requires much more voltage to sustain than a single arc of much greater length and this principle of arc extinguishment is utilized in the present invention. However, in constructions heretofore embodying a series of short arc gaps, the initial sparkover voltage has been largely determined by the number of such gaps, lowered to some degree by capacity and resistance elements, but lacking the novel features of the present invention which enables an actual total voltage applied to the gaps greater than the impressed voltage—a condition entirely distin-

guished from that of simply unbalancing the voltage applied to the individual gaps without any increase in sum.

Referring to Figs. 1, 2, 3, and 4, the embodiment of the invention shown includes a plate condenser comprising a stack of six plates of conducting material, consisting of the end or terminal plates 15 and 20, the centrally positioned pair of plates 17 and 18, and the intermediate plates 16 and 19. Each plate is insulated from every other by means of a disk of insulating material, the insulating disk 23 being interposed between the first and second plates, the disk 24 between the second and third plates, the disk 25 between the third and fourth plates, the disk 26 between the fourth and fifth plates, and the disk 27 between the fifth and sixth plates. The conducting plates and insulating disks are rigidly held in parallel abutting stacked relationship by means of the bolt 31 and cooperating nut 32, the bolt 31 extending coaxially through the stack, and being insulated from the conducting plates by means of the sleeve of insulating material 35.

The terminal plates 15 and 20 are provided with upwardly extending portions to which the terminal conductors 21 and 22 are respectively connected, as by soldering at 28 and 29, and the block of insulating material 30 spans the terminal conductors.

The assembly just described is contained in a housing of conducting material, including the hollow body portion 36 and the cover 37, the conductors 21 and 22 extending outwardly through the threaded nipple 38. For holding the assembly in spaced relationship with the wall of the hollow body portion 36, a plate of insulating material 34 is clamped between the head of the bolt 31 and the end plate 15, the plate extending outwardly beyond the plate assembly and being contoured to fit the inner surface of the body portion 36. A spring 33, of conducting material, is clamped between the terminal plate 20 and the nut 32, extending laterally on each side thereof and outwardly to engagement with one flat wall of the body portion 36, resiliently holding the head of the bolt 31 against the other flat wall of the body portion, thereby electrically connecting the terminal plate 20 to the body portion.

By means of suitably formed outwardly extending integral portions of the conducting plates, peripherally spaced spark gaps, positioned outwardly beyond the edge of the insulating disks, are provided. The plate 19 is provided with diametrically opposed outwardly and laterally extending portions, the respective ends of which extend near and in spaced relationship with outwardly extending portions of the plates 15 and 17, to provide the spark gap 10 between the plate 19 and the plate 15, and the spark gap 13 between the plate 19 and the plate 17. Similarly, along a diameter 60 degrees displaced from that of the outwardly extending portions of the plate 19, the plate 16 is formed with diametrically opposed outwardly and laterally extending portions, the respective ends of which extend near and in spaced relationship with outwardly extending portions of the plates 18 and 20, to provide the spark gap 11 between the plate 16 and the plate 20, and the spark gap 12 between the plates 16 and 18. The plate 17 is provided with a single outwardly and laterally extending portion, the end of which extends near and in spaced relationship with an outwardly extending portion of the plate 18, to provide the spark gap 14 therebetween.

It may be noted that a construction as above

described will yield the circuit arrangement diagrammed in Fig. 5. If the device is applied for the purpose of limiting the voltage of a conductor to ground, the terminal conductor 21 would normally be connected to the conductor the voltage of which it is desired to limit, and the terminal conductor 22 grounded. The insulating elements of the structure must be so coordinated with the conducting elements that sparkover occurs only via the spark gaps.

In addition, for proper operation of the device, cascade sparkover should be avoided; i. e. all of the gaps should sparkover at the same instant rather than an initial breakdown of one being relied upon to cause another to sparkover, which is a common occurrence in structures heretofore having capacitatively or otherwise unbalanced serial gaps.

Reference is made to Fig. 6 for the purpose of illustrating the manner in which device functions to accomplish concurrent sparkover of the serial arrangement of gaps. Fig. 6 is an equivalent circuit in which the condenser A may represent capacitance provided by the plates 15 and 16 and the insulating disk 23 therebetween; the condenser B the capacitance provided by plates 16 and 17 and the insulating disk 24 therebetween; the condenser C the capacitance provided by the plates 17 and 18 and the insulating disk 25 therebetween; the condenser D the capacitance provided by the plates 18 and 19 and the insulating disk 26 therebetween; and the condenser E the capacitance provided by the plates 19 and 20 and the insulating disk 27 therebetween.

The plates of the condenser and the thickness and character of the insulating material therebetween, may be as a convenient practical design, such that the equivalent capacitances of Fig. 6 are:

$$\begin{aligned} A &= 128 \text{ mmf.} \\ B &= 128 \text{ mmf.} \\ C &= 8 \text{ mmf.} \\ D &= 128 \text{ mmf.} \\ E &= 128 \text{ mmf.} \end{aligned}$$

When a voltage E is applied at the terminals,

$$Ea + Eb + Ec + Ed + Ee = E \quad (1)$$

Since equal voltages appear across equal capacitances,

$$Ea = Eb = Ed = Ee \quad (2)$$

And since voltage division across unequal capacitances in series is an inverse function of the capacitances,

$$Ec = \frac{128}{8} Ea = 16Ea \quad (3)$$

Solving for Ea in (1)

$$Ea + Ea + 16Ea + Ea + Ea = E, \text{ or} \\ 20Ea = E$$

$$Ea = \frac{E}{20}$$

and

$$Eb = \frac{E}{20}$$

$$Ec = \frac{16E}{20}$$

$$Ed = \frac{E}{20}$$

$$Ee = \frac{E}{20}$$

Voltage across gap 10 =

$$E_a + E_b + E_c + E_d = \frac{19E}{20} = 95\% E$$

Voltage across gap 11 =

$$E_b + E_c + E_d + E_e = \frac{19E}{20} = 95\% E$$

Voltage across gap 12 = $E_b + E_c = \frac{17E}{20} = 85\% E$

Voltage across gap 13 = $E_c + E_d = \frac{17E}{20} = 85\% E$

Voltage across gap 14 = $E_d = \frac{16E}{20} = 80\% E$

Total voltage on gaps = $\frac{88E}{20} = 440\% E$

Assume it is desired to limit the voltage across the terminals to 3000 volts. To assure concurrent sparkover of all five gaps in series, gaps 10 and 11 should be set to sparkover at 95% of 3000 volts; gaps 12, 13 should be set to sparkover at 85% of 3000 volts; and gap 14 should be set to sparkover at 80% of 3000 volts. These gap settings will be of the order of 32" electrode spacing. Under this condition, all gaps will sparkover concurrently when a voltage of 3000 volts appears at the terminals of the device, and the current path taken following sparkover will be through the entire series arrangement of gaps and condenser plates, in which series arrangement the group consisting of all of the odd numbered condenser plates are serially connected in series with the group consisting of all of the even numbered condenser plates.

It may be noted that the capacitance resulting from the cooperation of the centrally positioned plates (17 and 18) with the interposed insulating material (25) is common to all of the spark gaps. If the dimensions of the structure are such that this capacitance is substantially smaller than that of the condensers on each side of the centrally positioned plates, the increment in voltage added to each of the gaps which span one or more of the last-named condensers will be small, and the sparkover voltage of the entire series of gaps approaches that of the sparkover voltage of the centrally-positioned gap.

For certain low voltage applications, the interrupting ability of three spark gaps is all that is required. For such a construction, it will be clear that a four plate device, such as that shown diagrammatically in Fig. 7, will result by simply utilizing the intermediate plates 16 and 19 as the terminal plates, and omitting the plates 15 and 20, along with the insulating disks 23 and 27. This modification yields the circuit of Fig. 7, in which the terminal conductors 39 and 40 are respectively connected to the terminal plates 41 and 44. The pair of centrally positioned plates are indicated at 42 and 43, and the voltage-responsive serial arrangement of gaps and plates is, as above indicated, from the terminal conductor 39 through the plate 41; thence through the gap 45, thence through the plate 43, thence through the gap 46, thence through the plate 42, thence through the gap 47 to the plate 44, and through the latter to the other terminal conductor 40.

For best operation, it is desired that the voltage appearing across each gap reach the spark-over magnitude of all of the respective gaps concurrently, which is easily accomplished in the construction illustrated by simply regarding the coordination of the gaps with the condenser ele-

ments bridged thereby. It will be clear from the above description that this can be accomplished with any even number of condenser plates greater than four, and that in such a construction, the number of spark gaps which can be effectively used is one less than the number of plates of the structure.

In view of the above considerations, it is intended that the embodiments here described will be regarded as illustrative rather than limiting constructions.

I claim as my invention:

1. An arc interrupter comprising a plate condenser having an even number of at least four normally insulated conducting plates including a centrally-positioned pair of plates and an additional plate positioned adjacent to and at each side of said pair of plates, said plates being formed to provide a first spark gap between said centrally-positioned pair of plates, a second spark gap between one additional plate and that plate of said pair most remote therefrom, and a third spark gap between the other additional plate and the other plate of said pair, the series arrangement of said spark gaps and said centrally-positioned plates constituting a series circuit including the three spark gaps from said one additional plate to the other, said spark gaps being dimensioned to provide the weakest electrical path from said one additional plate to the other, and the capacitances as measured between each additional plate and the respective centrally-positioned plate being substantially equal and each capacitance being substantially greater than the capacitance as measured between said centrally-positioned plates.

2. An arc interrupter comprising a stack of normally insulated conducting plates including a pair of end plates and two centrally-positioned plates, each of said plates having an outwardly extending portion formed to provide spark gaps between certain of said plates for establishing a circuit which includes said spark gaps in series arrangement from one end plate to the other, two of said gaps being positioned respectively between the end plates and the respective remotest centrally-positioned plate, and one gap being positioned between the centrally-positioned plates, the arrangement being such that the weakest electrical path from one end plate to the other is via said dielectric circuit, and the capacitance between said centrally-positioned plates is small in comparison with the capacitance between each end plate and the respective adjacent centrally-positioned plate.

3. An arc interrupter comprising a stack including at least four normally insulated plates of conducting material consisting of a first plate, a second plate, a third plate and a fourth plate, insulating material interposed between the first plate and the second plate, insulating material interposed between the third plate and the fourth plate, and insulating material interposed between the second plate and the third plate, said last-named insulating material cooperating with said second and third plate to provide a capacitance substantially less than that provided by the cooperation of the insulating material with either the first and second plates or the third and fourth plates, means holding said plates in substantial coaxial alignment, and integral portions of said plates extending outwardly beyond said insulating material and arranged to form a spark gap between said second and third plates, a spark gap

between said first and third plates, and a spark gap between said second and fourth plates, the arrangement being such that sparkover between said first and fourth plates occurs preferentially through the series of the three spark gaps.

4. An arc interrupter comprising a stack of at least four normally insulated plates of conducting material including a serial arrangement of a first plate, a second plate, a third plate and a fourth plate, insulating material interposed between the first plate and the second plate, insulating material interposed between the second plate and the third plate, and insulating material interposed between the third plate and the fourth plate, said last-named insulating material cooperating with said last-named plates to provide a capacitance substantially equal to that provided by the cooperation of said first-named insulating material with said first and second plates and substantially greater than the capacitance resulting from the interposition of said insulating material between said second and third plates, means holding said plates in substantial coaxial alignment, and integral portions of said plates extending outwardly beyond said insulating material to form a series circuit arrangement which includes serially three spark gaps between said first plate and said fourth plate, said spark gaps being arranged to connect, in response to sparkover thereof, all of said plates in the series circuit arrangement in which said first plate connects to said third plate, said third plate to said second plate, and said second plate to said fourth plate.

5. An arc interrupter comprising a container of conducting material, a plate condenser therein having an even number of at least four conducting plates mounted in insulated relationship one to any other, said plates including a centrally-positioned pair of plates providing a predetermined capacitance there-between and terminal plates at the respective outer sides and adjacent to said pair of plates providing respective capacitances substantially greater than said predetermined capacitance, said plates being provided with outwardly extending portions formed to provide a spark gap between said centrally-positioned pair of plates, a spark gap between one terminal plate and that plate of said pair most remote therefrom, and a spark gap between the other terminal plate and the other plate of said pair, the series arrangement of said gaps establishing the weakest electrical path through said plates from one terminal plate to the other, means holding said plates in spaced parallel relationship, insulating means isolating one terminal plate from said container, and conducting means connecting the other terminal plate to said container.

6. An arc interrupter comprising a series of parallel conducting plates including a first, second, third, fourth, fifth and sixth plate, insulating material spacing said plates apart in normal insulated relationship, means insulated from said plates holding said plates in fixed position, peripherally spaced spark gaps associated with said plates arranged to provide a series arrangement

of spark gaps consisting of a spark gap between the first plate and the fifth plate, a spark gap between the fifth plate and the third plate, a spark gap between the third plate and the fourth plate, a spark gap between the fourth plate and the second plate, and a spark gap between the second plate and the sixth plate, said spark gaps being arranged to establish a preferential electrical path between said first plate and said sixth plate which includes in series circuit relation all plates therebetween, the plates so co-operating with the interposed insulating material that the capacitances between the first and second plates, the second and third plates, the fourth and fifth plates, and the fifth and sixth plates are substantially equal and each substantially greater than the capacitance between the third and fourth plates.

7. An arc interrupter comprising a stack of n parallel plates, n being an even number greater than two, said stack including a centrally-positioned pair of plates, insulating material spacing said plates apart in normally insulated relationship, means holding said plates in said insulated relationship, conducting means including said plates providing a preferential sparkover path from one end of said stack to the other, said sparkover path including at least three spark gaps connected in series circuit relationship from one end of said stack to the other and so related to said conducting plates that the capacitance formed by the cooperation of said centrally-positioned plates with the insulating material there-between is common to all three spark gaps, and substantially less than the capacitance formed by any other adjacent plates in co-operation with the insulating material there-between.

8. An arc interrupter comprising a stack of normally insulated plates of conducting material, one of said plates co-operating with another adjacent plate to provide a predetermined capacitance there-between and the remaining plates co-operating with respective adjacent plates to provide a plurality of substantially equal capacitances each substantially greater than said predetermined capacitance, and integral portions of said plates extending outwardly to form a series circuit arrangement including all of said plates and a plurality of spark gaps there-between, the arrangement being such that at least said predetermined capacitance is connected across each spark gap.
